ATTORNEY

UNITED STATES PATENT OFFICE.

WILLIAM H. WHEELER, OF NEW YORK, N. Y., ASSIGNOR, BY MESNE ASSIGNMENTS, TO FEDCO NUMBER PLATE CORPORATION, OF NEW YORK, N. Y., A CORPORATION OF DELAWARE.

IDENTIFICATION DEVICE AND METHOD OF PRODUCING SAME.

Application filed November 26, 1923, Serial No. 677,017. Renewed June 3, 1927.

This invention relates to improvements in identification devices of the general character disclosed in my copending applications, Serial No. 662,230 and 662,231, filed September 12, 1923, and to a novel method of manufacturing such devices.

It is an object of the present invention to provide an identification device, primarily intended for use upon motor vehicles which cannot be successfully imitated for an illegal purpose without great expense.

It is a further object of the invention to provide a novel method of manufacturing such devices which will render possible their production in large quantities at a relatively small expense, and yet a process which will render unauthorized duplication upon a small scale prohibitively costly, principally because of the apparatus necessary for performing the process.

It is a further object of the present invention to form an identification plate of the character stated from a single metal plate so treated that identifying characters, a background and a design on the background will present sharply contrasting colors.

With these and other objects in view, the invention consists in certain novel features of construction and combinations and arrangements of parts as will be more fully hereinafter described and pointed out in the claims.

In the accompanying drawings,

Fig. 1 is a perspective view of the metal blank from which my improved identification plate is formed.

Fig. 2 shows the blank embossed with a design,

Fig. 3 shows the embossed blank after the first oxidizing process has been performed.

Fig. 4 shows the embossed portion of the oxidized blank ground or cut to expose the design in bright metal,

Fig. 5 shows the blank after the second oxidizing operation has been performed and embossed identifying indicia substituted for the embossed design.

Fig. 6 is similar to Fig. 5, but showing the embossed identifying indicia ground or cut to expose the natural bright metal of the plate, and

Fig. 7 shows the plate in its final form.

Referring with particularity to the draw-

ings, it will be seen that I have used the reference character 10 to designate the blank from which my improved identification plate is formed. This blank may be of any convenient size and shape and is sufficiently thin to permit an embossing operation to be performed thereon. The plate is of some metal which will give at least two contrasting surface colors when oxidized at two different temperatures, or otherwise treated. The first step of the process consists in bright annealing the blank. In Figure 2, the first embossing operation has been performed. In this instance, I have shown a design consisting of a rectangular border 11, a central circular frame 12 for a name 13, and a distinguishing symbol 14, the name and the symbol being characteristic of the particular make of automobile for which the plate is intended. Between the frame and the border, there is shown a leaf design 15. The design which is disclosed in the accompanying drawings is merely for the purpose of illustration. Any design might be embossed upon the plate. The incorporation of the name of the car or some symbol characteristic of the car within the design is purely optional, although I have usually found the name desirable.

In Fig. 3, I have shown the appearance of the plate after it has been subjected to an oxidizing process at a relatively high temperature. If we assume for the sake of convenience that the plate is of nickel, its entire surface will have taken on a blue color, this color being indicated by the dark stipple of Fig. 3. Having oxidized the entire surface of the plate, the embossed design is ground or cut to expose the bright metal below the oxidized surface as seen in Fig. 4. The plate is then subjected to a second oxidizing process, this time at a lower temperature. The second oxidizing of the plate will of course not affect the blue background indicated at 16, but will turn the bright design to a light brown color, as indicated by the light stipple of Fig. 5.

Identifying indicia 17 are now embossed upon the plate, the same operation which effects the embossing of the indica, serving to eradicate the previous embossing. The plate after this much of the process has been performed is shown in Fig. 5, and Fig. 6

shows the plate subsequent to the next operation, which consists in grinding or cutting the embossed identifying indicia to expose the bright metal of the plate.

5 The next operation consists in re-embossing the plate preferably with the original design, although any suitable modification or variation thereof might be used. In fact, an entirely different design might be embossed upon the plate, but for the purpose of clearness of illustration, I have shown the original design re-embossed. The finished plate, therefore, consists of a dark background, light embossed design, and bright 10 identifying indicia which are embossed or not, depending upon whether they appear upon the background or the design. The finished plate may be spot welded or otherwise suitably attached to the engine block 15 or chassis frame of a motor vehicle. The manner of attachment or the part of the machine to which the plate is attached is immaterial to the present invention.

I have shown a dark background, light design, and lighter identifying characters, but either design, background or characters might be oxidized either a light or a dark color or left bright, as the case may be, and whether the background, the design or the 20 characters be embossed is immaterial to the invention. The process is considerably simpler than the processes shown in my previous applications, wherein laminated plates are treated and at the same time, the finished product is equally hard for an unauthorized person to duplicate.

Various slight changes and alterations 25 might be made in the general form and arrangement of the parts described without departing from the invention, and hence I do not wish to limit myself to the precise details set forth, but shall consider myself at 30 liberty to make such changes and alterations as fairly fall within the spirit and scope of the appended claims.

I claim:

1. A method of making metal identification plates which includes the steps of (1) subjecting a plate to chemical treatment to 35 change the surface color of the plate, (2) removing a part of such colored surface to expose the natural color of the metal, (3) subjecting the plate to a second chemical treatment to produce a different color on 40 that portion of the plate from which the previously colored surface has been removed, without affecting the color of the remainder of the plate surface.

2. A method of making metal identification plates which includes the steps of (1) subjecting the plates to heat treatment at a 45 relatively high temperature to change the surface color of the plate, (2) removing a portion of such colored surface to expose the natural color of the metal, (3) subject-

ing the plate to a second heat treatment at a lower temperature to produce a different color on that portion of the plate from which the previously colored surface has been removed.

3. A method of making metal identification plates which includes the steps of (1) oxidizing a metal plate at a relatively high temperature, (2) removing a portion of the oxidized surface, (3) oxidizing the plate at 75 a lower temperature whereby different portions of the surface of the plate will be differently colored.

4. A method of making metal identification plates which includes the steps of (1) 80 subjecting a plate to chemical treatment to change the surface color of the plate, (2) removing a part of such colored surface to expose the natural color of the metal, (3) subjecting the plate to a second chemical treatment to produce a different color on that portion of the plate from which the previously colored surface has been removed without affecting the color of the remainder 85 of the plate surface, (4) forming identification characters in the surface of the plate.

5. A method of making metal identification plates which includes the steps of (1) subjecting the plates to heat treatment at a 90 relatively high temperature to change the surface color of the plate, (2) removing a portion of such colored surface to expose the natural color of the metal, (3) subjecting the plate to a second heat treatment at a lower temperature to produce a different color on that portion of the plate from which the previously colored surface has been removed, (4) forming identification characters in the 95 surface of the plate.

6. A method of making metal identification plates which includes the steps of (1) oxidizing a metal plate at a relatively high temperature, (2) removing a portion of the oxidized surface, (3) oxidizing the plate at 100 a lower temperature whereby different portions of the surface of the plate will be differently colored, (4) forming identification characters in the surface of the plate.

7. A method of making metal identification plates which consists in the steps of (1) 105 embossing a design upon the plate, (2) oxidizing the plate to change the surface color thereof, (3) removing the colored surface of the embossed design to expose the natural color of the metal, (4) re-oxidizing the plate at a lower temperature to produce a new surface color on the design, (5) obliterating the embossing of the design and embossing identifying indicia upon the plate, (6) removing the colored surface of the identifying indicia to expose the natural color of the plate, and (7) re-embossing the original 110 design.

8. As a new article of manufacture, a plate of the class described bearing a design 115

in contrasting colors thereon, the colors constituting differently chemically treated surface portions of the plate.

9. As a new article of manufacture, a plate of the class described bearing a design thereon, the design being formed of differently heat treated surface portions of the plate.

10. As a new article of manufacture, a plate of the class described bearing a design thereon, the design being formed of differently oxidized surface portions of the plate.

11. As a new article of manufacture, a plate of the class described bearing a design thereon, the design being formed of bright portions and differently oxidized portions of the surface of the plate.

12. As a new article of manufacture, a plate of the class described, the surface of said plate embodying a background, a design and identifying indicia, said background and design being formed of differently oxidized portions of the plate surface.

13. As a new article of manufacture, a plate of the class described, the surface of the plate embodying a background, a design and identifying indicia, said background and design being formed of differently oxidized portions of the plate surface and the indicia being formed of a bright metal surface.

14. As a new article of manufacture, a plate of the class described, the surface of said plate embodying a background, a de-

sign and identifying indicia, said indicia, design and background being of contrasting colors, at least two of which constitute differently heat treated surface portions of the plate.

15. As a new article of manufacture, a plate of the class described, the surface of said plate embodying identifying indicia, the surface of said plate also embodying a background and a design, said background and design being of contrasting colors and comprising differently heat treated surface portions of the plate.

16. As a new article of manufacture, a plate of the class described, the surface of said plate embodying identifying indicia, the surface of said plate also embodying a background and a design, said background and design being of contrasting colors and comprising differently heat treated surface portions of the plate, the surface of said background and the design being disposed in different planes.

17. As a new article of manufacture, a plate of the class described, the surface of said plate embodying identifying indicia, the surface of said plate also embodying a background and a design, said background and design being of contrasting colors and comprising differently heat treated portions of the plate surface, said design being embossed upon the plate.

WILLIAM H. WHEELER.
